UNITED STATES PATENT OFFICE.

EVERETT E. YATES, OF ANCRAK LEAD MINES, NEW YORK.

CLOTHES-WASHING DEVICE.

1,118,996.

Specification of Letters Patent.

Patented Dec. 1, 1914.

Application filed December 17, 1913. Serial No. 807,300.

To all whom it may concern:

Be it known that I, EVERETT E. YATES, a citizen of the United States, residing at Ancram Lead Mines, in the county of Columbia, State of New York, have invented certain new and useful Improvements in Clothes-Washing Devices; and I do hereby declare the following to be a full, clear, and exact description of the invention, such as will enable others skilled in the art to which it appertains to make and use the same.

The present invention is directed to clothes washing devices, and more particularly to that type known as pounders.

15 The invention has for its object to construct a device of this character which may be used for cleansing clothes when submerged in water by reciprocating the same.

A further object of the invention is to 20 provide a clothes pounder so constructed that a partial vacuum will be obtained during the upward movement of the device, thereby insuring thorough cleaning of the clothes.

25 With these and other objects in view, this invention resides in the novel features of construction, formation, combination and arrangement of parts to be hereinafter more fully described, claimed and illustrated in the accompanying drawing, in which:—

Figure 1 is a side elevation of the device. Fig. 2 is a vertical central sectional view through the same. Fig. 3 is a bottom plan view. Fig. 4 is a sectional view on line 35 4—4 of Fig. 2.

Referring to the drawing, the numeral 1 designates a tubular handle, the upper end of which is closed by a threaded cap 2, said cap having the vent opening 3 formed in its 40 top, the purpose of which will appear later.

The lower end of the handle 1 is provided with an annular shoulder 4 which limits the downward movement of the cylindrical hollow valve 5. The lower end of the handle 45 is further provided with a nozzle 6.

A conical head 7 is provided and has its minor end secured in any suitable manner to the lower end of the handle 1, and in a position so that the nozzle 6 will extend into 50 the upper end of the head.

Ports 8 are formed in the head 7, the same being disposed diametrically opposite, said ports being protected by guards 9, which have their upper ends closed and their lower ends open, said guards being 55 semi-circular in cross section so that passageways 10 are provided for communication with the ports 8. The guards 9 will prevent clothes from being sucked into engagement with the ports 8 during the reciprocation of the device, while the ports will 60 permit free circulation of water through the head upon certain movement of reciprocation thereof.

Guard bars 11 are arranged in the major 65 end of the head to prevent the clothes being washed from entering the head, said bars also serving as beaters to aid in removing the dirt from the clothes.

In operation the device in its downward 70 movement will contact with the submerged clothes, whereupon the water entering the head will force the valve 5 upwardly. Water will also pass through the ports 8 and will exit through the passages 10 until 75 the water closes the ports 8, whereupon a partial vacuum is formed in the upper end of the head. On the upstroke of the device the water in the handle will rush therefrom, after which the valve will seat upon the 80 annular shoulder 4 so that the partial vacuum in the upper end of the head will be retained until the water uncovers the ports 8, the vacuum serving to create suction which greatly aids in cleaning the clothes. 85

By providing the vent opening 3 in the cap the hollow valve 5 may move upwardly.

What is claimed is:—

The combination with a tubular handle having an apertured closure at the upper 90 end thereof, of a hollow conical head connected at its apex with the lower end of the tubular handle, said head having an aperture in the apex thereof, a tubular nozzle connected with the lower end of the 95 handle and extending through the opening in the apex of the head and having its upper end portion projecting into the handle and its lower end portion projecting into the head, a hollow cylindrical valve slid- 100

able in the handle and adapted to rest upon and close the upper end of the nozzle, said hollow head having air ports formed in the side wall thereof, and a hollow guard member for each port attached to the outer wall of the conical head, the upper end of each guard member being closed and the lower end thereof open.

Copies of this patent may be obtained for five cents each, by addressing the "Commissioner of Patents, Washington, D. C."

In testimony whereof, I affix my signature, in the presence of witnesses.

EVERETT E. YATES.
